WELL DEVELOPER

Robert L. Clark, Indianapolis, Ind.

Application May 9, 1958, Serial No. 734,154

3 Claims. (Cl. 166—177)

This invention relates to a tool for developing wells, primarily water wells. The making of a well consists of more than simply drilling a hole in the earth down into the water vein. When the well has been initially drilled to the desired depth, and the drill hole has been supplied with casing, there remains the job of what is well known as developing the well.

This developing of the well consists in forming, in effect, a water reservoir about the lower end of the casing or end of the drill hole by removing fine particles such as sand and clay so that, in a gravel well, there remains about the lower end of the drill hole a zone of washed out gravel, from between the stones and pebbles of which, the sand and clay is removed to leave interstices filled with water so that there may always be a considerable volume of water about the lower end of the well, this reservoir being filled by inflow from the general vein of water.

Unless the well is developed in this manner by removing such fine material, the well will not operate satisfactorily since the screen at the lower end which is usually provided will become clogged with the fine particles to the extent that water may not be lifted in the casing. Also in the event that such sand does break loose to provide openings into the screen, that sand will continue to be pumped up to the detriment of pumps themselves, cutting away valve seats or where jets are used cutting away the Venturi throat, and in general producing very undesirable results.

My invention provides a tool utilized solely for the purpose of developing a well as above indicated. The tool is employed to not only "surge" the water in the casing particularly at the bottom thereof to agitate and break loose the fine particles in the coarser gravel or in fissures of rock where the lower end of the well penetrates rock. Not only is the tool employed for surging, but it also is employed to lift the sand up out of the casing by maintaining it in such an agitated state that it will remain in suspension rather than precipitate out in the lifting action.

In addition to the foregoing purposes, the tool is particularly conceived to avoid sand locks; to permit easy insertion into the casing; easy removal from the casing; and permitting an easy fabrication of the tool with low upkeep in the highly abrasive field.

These and many other objects and advantages of the invention will become apparent to those versed in the art of well drilling, and from the following description of one particular form of the tool which is illustrated in the accompanying drawing, in which:

Fig. 1 is a view in central vertical section through a construction embodying the invention as contained within a well casing; and

Fig. 2 is a like view in longitudinal central section of the device wherein the tool has been operated to an upper end of a lift action.

Referring to the drawing, the usual and well known casing indicated by the numeral 10 is provided in the drill hole, and there may be or may not be a screen 11 fixed at the lower end of the casing 10, depending upon whether

or not the well is drilled into gravel or stops at an upper surface of rock or even penetrates the rock. The screen 11 will be normally used in a gravel well.

An upper valve cage 12 has an upwardly extending, 5 conically formed stem 13 externally threaded to receive thereover a collar 14 attached to the usual well driller's cable (not shown). This forms what is termed in the trade as an API tool joint.

The cage 12 has an external diameter less than the 10 internal diameter of the casing 10, and is provided with a plurality of windows 15 therethrough spaced circumferentially around the cage. A valve disc 16 made out of any suitable pliable elastic material such as rubber is carried in the cage 12, by means of an under-weighted 15 body 17 from which a stem 18 extends upwardly through the disc 16, and through an upper confining plate 19 to receive a nut 20 thereon screw-threadedly as a means for compressing the plate against the disc 16 to retain it seated on the body 17. The body 17 has a diameter 20 less than the diameter of the disc 16.

The peripheral portion of the disc 16 exposed from the underside around the body 17 seats normally on the upper end of a nipple 21 which screw-threadedly enters the underside of the cage 12. As is indicated, the upper 25 end of the nipple 21 is provided with a planar end affording a flat seat against which the planar underside of the disc 16 bears.

The external upper end portion of the nipple 21 is 30 threaded not only to enter the cage 12, but also to receive a lock nut 22 to abut the lower end of the cage 12 so that the cage 12 does not become accidentally loosened or displaced from the nipple 21.

The nipple 21 is provided with a shoulder 23 on which 35 is seated an annular packing ring 24 having an external diameter slightly less than the internal diameter of the casing 10 so that a clearance normally may be had between the external, circumferential surface of the ring 24 and the inner side of the casing 10. In a four inch casing, this clearance would be approximately one sixteenth of an inch. The spacing of the shoulder 23 from the lock nut 22 is made to be such that there is a slight 40 clearance between the topside of the packing ring 24 and the underside of the nut 22. That is, the packing ring 24 is free to travel within the limited confines of the shoulder 23 and the underside of nut 22. The ring 24 will expand into a compressive sliding fit with the casing under pressure exerted by a column of water thereabove.

Holes 25 are drilled through the nipple 21 at the 45 upper level of the packing ring 24. These holes are centered in a common plane around the nipple herein shown as immediately below the lock nut 22. Preferably the nipple 21 is milled as at 26 to provide a cavity surrounding the outer ends of these holes 25 immediately at the top end of the packing ring 24.

The shoulder 23 is on the topside of a land 27 of the 50 nipple 21 which approaches the inner side of the casing 10 with a free sliding fit, this particular fit not intended to be a sealing fit since the packing ring 24 performs the sealing function.

An outer sleeve pipe 28 enters by its upper end screw-threadedly into the lower end of the nipple 21, providing a smooth passageway through the nipple 21 from the valve disc 16 and into the sleeve pipe 28. This sleeve pipe 28 is provided with a number of holes 29 there-through immediately below the lower end of the nipple 21. Other holes 30 are provided through the sleeve pipe 28 intermediate its ends.

The lower end of the sleeve pipe 28 carries a head 31 70 which has a portion extending inwardly to form an internal, upwardly presented annular shoulder 32. The external diameter of the sleeve pipe 28 is considerably less than is the internal diameter of the casing 10.

An inner tube 33, open at both ends, has an upper head 34 as a continuation of the tube 33, and provides an external surface in sliding contact with the internal side of the outer sleeve pipe 28. The outer diameter of the inner sleeve tube 33 is less than the internal diameter of the outer sleeve pipe 28 so that there is an annular clearance therearound. The head 34 will strike the shoulder 32 if the inner sleeve tube 33 is allowed to drop downwardly within the pipe 28, and thus arrest further longitudinal travel downwardly of the tube. This lowermost travel is indicated in Fig. 2, whereas in Fig. 1, the tube 33 is at approximately its upper limit of travel relative to the surrounding sleeve pipe 28. For purposes which will hereinafter be described, a bolt 35 may be passed through holes 30 in the pipe 28, and holes 36 provided through the tube 33 at various positions along its length. The bolt 35 may be secured in place by a nut 37. In this manner, relative travel between the tube 33 and its surrounding pipe 28 is prevented.

The tube 33 has screw-threadedly engaged on its lower end a lower valve cage 38. This lower valve cage 38 serves as a stop, when the bolt 35 is removed, limiting the upper travel of the tube 33 within the pipe 28.

This cage 38 is a duplicate of the cage 12, and carries therewithin the valve disc 39 which seats on the flat end of a nipple 40 screw-threadedly engaging through the lower end of the cage 38. Above the disc 39 and through the side wall of the cage 38 are a plurality of entry and exit windows 41. The external diameter of the cage 38 is less than the internal diameter of the casing 10 so that there may be flow of water or other fluid encountered in the well therearound. A collar or lock nut 42 also screw-threadedly carried on the nipple 40 abuts the lower end of the cage 38 so as to secure it fixedly on the nipple 40. A packing ring 43 surrounds the nipple 40 immediately below the collar 42, and between the packing ring 43 and the underside of the collar 42 are a plurality of holes 44 affording passageways over the top of the packing ring 43 and into the inside of the nipple 40.

A collar 45 carries an annular, inwardly extending head 46 which bears upon an outwardly and annularly extending foot 47 on the lower end of the nipple 40. The collar 45 extends below the lower end of the nipple 40 and screw-threadedly engages a collar 48. The collars 45 and 48 have external diameters less than that of the internal diameter of the casing 10. The lower end of the collar 48 may be shaped as may be desired depending upon what is encountered at the lower end of the casing. Where there is a screen 11 at the lower end of the casing 10, the collar 48 may be shaped to swage that screen into intimate contact with the casing. On the other hand, some installations require a lead packing which also may be swaged into position by the lower end of the collar 48. In wells in rock, the lower end of the collar 48 may even rest on the rock itself. Therefore the particular shape of the lower end of the collar 48 may vary all as is well known to those versed in the art, and this shape does not enter into the present invention per se. The packing ring 43 has freedom to travel slightly longitudinally of the nipple 40 between the collar 42 and the collar 45. This packing 43 is made out of a suitable resilient and elastic material such as rubber, so that it may expand and form a tight seal against the inside of the casing 10.

A suction or tail pipe 49 is screw-threadedly engaged in the lower end of the collar 48 where a screen 11 is employed, and this tail pipe 49 will extend well down within the screen 11. The tail pipe 49 is perforated by holes 50 therearound and throughout its length.

Operation

After the drilling operation has been completed and the casing 10 driven down to its final position, the construction above described is lowered into the casing 10

by being carried by the member 14. It is lowered in the casing 10 until the tail pipe 49 is entered within the screen 11, preferably with the collar 48 resting on the top of the screen, and the packing 43 is in compressive contact with the inside of the casing 10. However, before lowering the tool into the casing 10, the bolt 35 has been removed. The member 14 is then reciprocated in the usual manner vertically within the casing 10, so that the upper valve cage 12 is reciprocated likewise 10 while the lower cage 38 remains stationary. The reciprocation of the valve cage 12 is limited in extent by the degree of permissible travel of the pipe 28 along the then stationary inner tube 33 without violently striking the lower head 31 against the head 34. In this reciprocating action, the disc 16 lifts from the end of the nipple 21 as the water surges upwardly from the pipe 28, and the disc 39 of the lower valve is firmly seated. The uplift of the valve cage 12 then carries the liquid upwardly in the casing 10 whereupon the disc 39 will lift 15 and allow additional liquid to flow in from through the tail pipe 49 primarily. In this manner, a simple pump is maintained with the pipe 28 reciprocating longitudinally of the tube 33. This will tend to carry upwardly under the inflow of water through the screen 11 sand and clay particles even in colloidal suspension.

However this simple pumping action is not normally sufficient to develop the well properly, and after the initial pumping, the entire assembly may be lifted with the member 14 and the bolt 35 installed to interconnect the outer sleeve pipe 28 and the inner sleeve tube 33 so that they cannot travel one relative to the other. Then the device so fixed is lowered again into the casing 10, and reciprocated upwardly and downwardly so as to set up an extreme agitation and surging action of the water 20 below the device, the packing 43 in this instance traveling with the device up and down within the casing. This surging and agitating of the water within the casing 10 will tend to break loose any of the sand and clay particles which will have tended to have clogged the openings in 25 the screen 11, and also, most importantly, will have forced water outwardly in streams through the screen 11 to disturb and release the sand particles from their engagement with the larger pebbles or rocks in the zone of gravel about the screen. This breakloose of the sand and clay particles and even limestone particles is necessary in order to develop the reservoir as above indicated. After a period of this surging action, the device 30 is then pulled from the casing again, and the bolt 35 is removed, so that the pumping action can then be re-stored. In this pumping action, there is set up considerable agitation by reason of the construction of the diametrically spaced apart tube and pipe with the holes 35 extending through their sides throughout their lengths. In other words, not all of the liquid is lifted on an up-stroke of the upper cage 12, but quite a bit of it will 40 surge outwardly through the holes in one part of the stroke, and then will enter again into the pipe and tube on another cycle of the stroke so that the fluid is continually being agitated at all times aiding in preventing precipitation of the foreign particles in the water. The collection or sedimentation of sand about the packings 24 and 43 is avoided so that there is no sand locking of these members between the carrying nipples and the casing by reason of the provision of the holes 25 and 44 and the 45 milled out passageways 26 so that instead of having a quiet zone at these locations, water is flowing in and out to avoid the collection of the foreign material, particularly sand in those zones.

Holes 29 in the pipe 28 and the tube holes 36, particularly adjacent the head 34, avoid damaging concussion by releasing flow slightly through the holes, as the upper cage 12 is reciprocated with its appended parts.

Thus by following this operation, the water may be cleared shortly after the working loose of the clay and sand and then lifting it out of the well. When the well

is cleared and properly developed, then the device may be lifted therefrom, and the two cages 38 and 12 close coupled by sliding the tube 33 inwardly of the pipe 28 and inserting the bolt 35 again as above described so that the tool may then be carried about with less difficulty by reason of its lessened overall length.

Reference has been made above to the collar 45 being slidably carried on the lower end of the nipple 40 within the limits of the underside of the packing ring 43 and the outwardly extending portion 47. By reason of this construction, the entire weight of all of the construction carried above by the lower valve cage 38 may rest directly upon the packing ring 43 when the lower collar 48 is seated and stopped by any element in its path, such as the screen 11. In this manner, the packing ring 43 is spread laterally into a full sealing contact so that there be no passage of water therewith externally of the nipple 40. By removing the weight, that is by pulling upwardly on the member 14, the load is taken off of the packing ring 43, and due to its elasticity, it will of course return to its normal contracted state and thus be easily removed from within the casing 10. The packing 43 will come into sufficient compressive sliding contact with the inside of the casing 10 to permit the sloshing up and down of the water within the casing during the surging action.

Therefore while I have herein shown and described one particular form of my invention, it is obvious that structural changes may be employed without departing from the spirit of the invention, and I therefore do not desire to be limited to that precise form beyond the limitations which may be imposed by the following claims.

I claim:

1. A well developing device for use within a casing comprising an upper valve cage reciprocable within the casing, said cage having a fluid passage extending lengthwise therethrough and communicating with an opening into the casing; a packing ring carried by the cage slideable along the casing; an outer sleeve pipe of less diameter than the internal diameter of the casing and suspended from the valve cage; said pipe communicating with said fluid passage and being perforated adjacent said cage; an

inner tube perforated and reciprocable within and extending by a lower end from said pipe; said pipe and tube having flow clearance therebetween; an abutment at the lower end of said pipe; an abutment extending from the upper end of said tube in the path of the pipe abutment arresting travel of the tube from the pipe; a lower valve cage carried by said inner tube end, said lower cage having a fluid passage extending lengthwise therethrough communicating with said inner tube and communicating with an opening into the casing; a packing ring carried by said lower valve cage; a collar carried by and longitudinally reciprocable of said lower cage; said collar supporting vertically said lower cage and communicating with said fluid passage therethrough; said lower cage having a shoulder under which its said packing ring is positioned and the weight of said two cages and said pipe and tube being supported by said shoulder riding on said lower packing ring in turn supported by said collar when held against downward travel; and a valve disc in each of said cages, the disc in the upper cage normally closing off communication between its said fluid passage and said pipe, and the disc in the lower cage normally closing off communication between its said fluid passage and through said collar, both discs being lifted by fluid pressure thereagainst upon downward travel of the cages.

2. The structure of claim 1 in which holes in both said pipe and tube may be transversely aligned and a bolt is extended through both the pipe and the tube aligned holes to retain the pipe and tube against travel one in relation to the other.

3. The structure of claim 1 in which said upper cage also has a shoulder under which the upper cage packing ring is retained; said cages having washing out passageways over both of said rings from the casing sides thereof into the cages below said discs.
